HANDGRIP

John A. Griffin, Salt Lake City, Utah

Application January 2, 1952, Serial No. 264,386

4 Claims. (Cl. 273—75)

1

This invention relates to a novel handgrip for handles of various types, such as golf clubs, baseball bats, tennis rackets, hammers, hatchets and other tools, and has for its primary object to provide a handle grip formed entirely of hard twine or cord and which is more effective than handgrips of rubber, leather and tape since it will keep the hand dry and prevent slippage of the hand relatively to the handgrip due to moisture caused by perspiration.

Another object of the invention is to provide an extremely effective handgrip capable of being applied to handles of any cross sectional size and shape and which may be made in various lengths to be gripped by one or both hands.

A further object of the invention is to provide a novel handgrip which cannot become loose, which is incapable of unraveling and which is securely and effectively anchored to the handle.

Various other objects and advantages of the invention will hereinafter become more fully apparent from the following description of the drawing, illustrating a presently preferred embodiment thereof, and wherein:

Figure 1 is a side elevational view, partly in section, showing the handgrip applied to a handle;

Figure 2 is a side elevational view of a portion of the handgrip in an applied position;

Figure 3 is a fragmentary plan view of a portion of one end of the handgrip shown in a spread condition to illustrate the construction thereof;

Figure 4 is a perspective view of a portion of one end of the handgrip shown on a handle and spread to illustrate the construction thereof, and

Figure 5 is a fragmentary plan view of one preferred form of the intermediate portion of the handgrip.

Referring more specifically to the drawing, the handgrip in its entirety is designated generally 7 and is illustrated in Figure 1 applied to a handle A which may constitute a part of a hand tool or of an athletic implement. In its preferred embodiment as illustrated in the drawings, the handgrip 7 includes an intermediate portion 8 and corresponding end portions 9. Each end portion 9 is composed of an inner shoulder or abutment section 10 and an outer anchoring section 11.

In the preferred embodiment as illustrated in the drawing, the intermediate section 8 comprises a closely coiled braided ribbon formed of twine. As illustrated in Figure 5, the braided ribbon 12 is formed of seven strands 13 of hard twine which are tightly braided to form a flat braided ribbon which is then wound in tight convolutions about the handle A. The unbraided ends 14 of the ribbon 12 are disposed against the end convolutions

2

of the grip portion 8, as illustrated in Figure 2. The grip portion 8 may be cemented to the handle A, if desired, or if preferred the unbraided ends 14 of the strands may be temporarily secured to the handle A to hold the grip portion 8 in a properly applied position until the handgrip is completed. The number of strands 13 forming the flat braided ribbon 12 may vary and may comprise 3, 5 or 9 strands rather than 7 as illustrated. Likewise, if preferred, the intermediate portion 8 may be formed from a single strand of hard twine wound in tight convolutions about the handle A.

As the end portions 9 are identical, a description of one will suffice for both. The inner shoulder or abutment section 10 of each end portion 9 is composed of two strands 15 and 16 of hard twine which are inter-twisted with one another and wound in tight convolutions about an end of the grip portion 8. The intermediate portions of the strands 15 and 16 are twisted together to form a twisted portion 17 intermediate of the ends of the two strands 15 and 16 and the portion of the strand ends 15 and 16 which extend from the two ends of the twisted portion 17 are inter-wound or twisted with portions of the opposite ends of said strands to form a plurality of longitudinally and circumferentially spaced twisted portions 18 and 18a. The twisted portions 18 are each formed of two strand portions and the twisted portions 18a each include a third strand portion. The ends of the strands 15 and 16 are thus wound about an end of the grip portion 8 in a direction outwardly thereof to form closely coiled convolutions composed of circumferentially spaced twisted portions 18 and 18a. The four ends 15a and 16a are inter-twisted as seen at 19 in Figure 3 in groups of two strand ends and wherein the two groups are circumferentially spaced, only one of which being illustrated in Figure 3. The twist 19 may be formed either by the two ends of either the strand 15 or the strand 16 or by a strand end 15a and a strand end 16a. The strand ends 15a and 16a extend outwardly from the terminal twists 19 longitudinally of the handle A and are securely anchored beneath the anchoring section 11 which is complementary to and disposed outwardly of said shoulder or abutment section 10. The anchoring section 11 is formed similarly to the abutment section 10 from two strands 20 and 21 of hard twine the intermediate portions of which are twisted together at 22. The twisted portion 22 corresponds to the twisted portion 17. However, the anchoring section 11 differs from the abutment section 10 in that the convolutions extend inwardly of the handgrip 7 from the twisted intermediate portion 22 of the strands

which forms a part of the outer convolution thereof, and the ends of the strands 20 and 21 from the ends of the intermediate twisted portion 22 are inter-twisted with one another to form circumferentially spaced twisted portions 23 and 23a formed of two and three strand portions, respectively, corresponding to the twisted portions 18 and 18a. The inner ends of the anchoring section 11 which terminates against the outer end of the adjacent shoulder section 10 is finished off in a slightly different manner since the strand terminals cannot be anchored beneath the convolutions of the section 10. Accordingly, two of the strand terminals 20a and 21a which are extending in opposite directions are tightly inter-twisted with one another, as illustrated in Figures 3 and 4 at 24. The other terminal of the strand 20 extends from an end of one of the twists 23 and said terminal 20b is ended off by being twisted as seen at 25 with one of the strand portions leading into the terminal twist 24. The other terminal 21b is similarly tied off by means of a terminal twist 26, formed by twisting the strand terminal 21b, where it extends from a twisted portion 23 about the other strand portion leading to the terminal twist 24.

The outer anchoring sections 11 are drawn up tightly with their convolutions in closely abutting engagement and with the inner convolutions of each anchoring section 11 in tight abutting engagement with the outer convolutions of the adjacent abutment sections 10, which have previously been tightened so that the convolutions thereof are in closely abutting engagement. The terminals 15a and 16a of each abutment section 10 which extend outwardly from beneath the outer convolutions of the adjacent anchoring section 11 are cut off at the outer edge of said anchoring section 11 and the terminals 20 and 21a are likewise cutoff at the inner edge or convolution of each anchoring section 11 and are held from untwisting by the tight abutting engagement of the twists 24, 25 and 26 with the adjacent convolution of the adjacent abutment section 10, which additionally holds the terminals 20b and 21b which are likewise cutoff at terminals of the twists 25 and 26.

From the foregoing it will be readily apparent that the handgrip 7 as thus assembled will be effectively maintained in its applied position on the handle A as illustrated in Figure 1. If desired and to more securely apply the handgrip 7, the sections 8, 10 and 11 thereof may be cemented to the handle portion A around which they are applied and the end portions of the intermediate section 8 may be cemented likewise on their outer sides so that the end sections 9 will be bonded thereto.

It is to be noted that the end sections 9 are tapered outwardly as illustrated in Figure 1 due to the fact that the outer part of each anchoring section 11 engages a portion of the handle A while the inner part thereof and the abutment section 10 is applied over an end of the intermediate section 8. The shoulder or abutment sections 10 thus form enlargements adjacent the ends of the intermediate section 8, which is gripped by the hand, to prevent the hand from slipping lengthwise on the handgrip 7. Obviously, the length of the intermediate section 8 may vary between the abutment sections 10 depending upon whether it is to be gripped by one or both hands.

Various modifications and changes are contemplated and may obviously be resorted to,

without departing from the spirit or scope of the invention as hereinafter defined by the appended claims.

I claim as my invention:

1. An implement handgrip comprising an elongated intermediate portion and corresponding end portions, said intermediate portion being formed of twine adapted to be wound about an implement handle in closely wound convolutions, each of said end portions including an abutment section and an anchoring section, each abutment section being disposed around an end of the intermediate portion for anchoring said end of the intermediate portion to the handle and for forming an enlargement at the end of the handgrip, each of said anchoring sections being disposed around the handle beyond the outer end of the adjacent abutment section and in abutting engagement therewith, said abutment sections and anchoring sections each being formed of twine and each including a plurality of separate lengths of twine, and the terminals of the lengths of twine of the abutment sections being anchored beneath the anchoring sections and against the handle.

2. A handgrip as in claim 1, each abutment section being formed of two lengths of hard twine wound in close convolutions outwardly toward an end of the handgrip from adjacent said end including a plurality of circumferentially spaced twisted portions interposed between untwisted intermediate portions, said twisted portions including a twisted portion at the inner end of the abutment section formed by the intermediate portions of the two lengths of twine, the outer convolution of said abutment section being formed by end portions of the two lengths and the terminals of said end portions extending from said outer convolution in a direction away from the abutment section and longitudinally of the handle.

3. A handgrip as in claim 2, each of said anchoring sections being formed of two lengths of twine wound inwardly of the handgrip in close convolutions including a plurality of circumferentially spaced twisted portions interposed between untwisted portions of the twine lengths, one of said twisted portions being formed by the intermediate portions of the two lengths and constituting a part of the outer convolution of the anchoring section, the inner convolution of the anchoring section including a plurality of circumferentially spaced twisted portions formed by the terminals of the two lengths, said last mentioned twisted portions being disposed in tight abutting engagement with the outer convolution of the adjacent abutment section.

4. A handgrip as in claim 1, said end portions each being formed of a plurality of lengths of twine including two lengths forming the abutment section thereof and two strands forming the complementary anchoring section, said intermediate portion and end portions of the handgrip being bonded to the handle and to one another.

JOHN A. GRIFFIN.
